UNITED STATES PATENT OFFICE.

EDWARD H. SCOFIELD, OF MINNEAPOLIS, MINNESOTA.

BRAKE-HANGER.

No. 817,994.

Specification of Letters Patent.

Patented April 17, 1906.

Application filed January 23, 1904. Serial No. 190,282.

To all whom it may concern:

Be it known that I, EDWARD H. SCOFIELD, a citizen of the United States, residing at Minneapolis, in the county of Hennepin and State of Minnesota, have invented certain new and useful Improvements in Brake-Hangers; and I do hereby declare the following to be a full, clear, and exact description of the invention, such as will enable others skilled in the art to which it appertains to make and use the same.

My invention has for its object to provide an improved brake-hanger; and to this end it consists of the novel devices and combinations of devices hereinafter described, and defined in the claims.

The improved brake-hanger is illustrated in the accompanying drawings, wherein like characters indicate like parts throughout the several views.

Figure 1 is a view, principally in side elevation, but with some parts sectioned on the line $x' x'$ of Fig. 2, showing one of my improved brake-hangers applied to support a brake head and shoe from a truck-frame, parts of the truck-frame being broken away and one of the truck-wheels being indicated in part by dotted lines. Fig. 2 is a front elevation of the mechanism shown in Fig. 1, but with the brake-shoe removed and with one of the longitudinal bars of the truck-frame sectioned on the line $x^2 x^2$ of Fig. 1. Fig. 3 is a section on the line $x^3 x^3$ of Fig. 2. Fig. 4 is a section on the line $x^4 x^4$ of Fig. 3. Fig. 5 is a plan view showing one corner portion of the truck-frame. Fig. 6 is a plan view showing one of the brake-heads and a portion of the brake-beam, to one end of which the said head is rigidly attached; and Fig. 7 is a detail view in plan showing the so-called "thrust-sleeve" of the brake-hanger.

The numeral 1 indicates one of the longitudinal side bars, and the numeral 2 one of the transverse end bars, of the truck-frame, which truck-frame may be of ordinary or any suitable construction.

In Fig. 1 the curved dotted line (marked 3) indicates the peripheral line or face of one of the truck-wheels.

The numeral 4 indicates one of the brake-heads, to which is detachably secured a brake-shoe 5, shown as held thereto by a long curved key 6, passed through perforations in the interlapping lug portions of the said head and shoe.

The numeral 7 indicates the compression-bar, and the numeral 8 the tension or truss rod, of the brake-beam, to each end of which beam of course one of the brake-heads 4 is rigidly secured in the usual or any suitable way.

Bolted or otherwise rigidly secured on the transverse end bars 2 are brake-supporting brackets 9, only one of which is shown in the drawings. This bracket 9 is provided with an inwardly-projecting segmental bearing-web 10, which is bifurcated or slit at 10^a, as best shown in Figs. 2 and 3, and for a purpose which will presently appear. The sections of the bifurcated segmental web 10 are strengthened by vertical ribs 10^b, cast integral therewith and with the body of the bracket 9.

The brake-head 4 in its upper end is formed with an inverted pocket-like seat 11 and is bifurcated or split above said pocket, as shown at 12. The slit 12 is much narrower than the pocket 11 and opens centrally into the upper portion thereof. Above the pocket 11 the brake-head is formed with a segmental bearing-surface 13, which extends concentric to the upper portion of said pocket and extends transversely of the head approximately the width of the said pocket.

The brake-hanger proper is composed of a headed bolt 14 and a thrust-sleeve 15, mounted thereon. At its lower end the bolt 14 is provided with a transversely-extended head 16, which in cross-section is cylindrical and fits the upper cylindrical bearing-surface of the pocket 11 of the brake-head. The body 17 of the bolt works pivotally through the seat 12 of said brake-head and through the slit 10^a of the segmental bearing-web 10 of the bearing-bracket 9. The semicylindrical rocker 17 or bearing-block 17 fits and works upon the upper cylindrical surface of the segmental bearing-web 10. The screw-threaded upper end of the bolt 14 is passed through a perforation in the central portion of the rocker 17 and above said rocker is provided with a pair of lock-nuts 18. The thrust-sleeve 15 is formed in its ends with transversely-extended cylindrical depressions or seats that engage one with the lower cylindrical portion of the web 10 and the other with the cylindrical bearing-surface or shoulders 13 on the brake-head 4.

When the nuts 18 are removed from the bolt 14 or are sufficiently loosened up thereon and when the brake-shoe 5 is removed

from the head 4, the said bolt may be inserted, with its head 16, in working position within the seat 11 of the said head either by an endwise upward movement or by a laterally and slightly upward movement. When the parts of the brake-hanger are applied in working position, as shown in the drawings, the nuts 18 should be so set that all play between the thrust-block 15, bolt-head 16, and rocker 17 and engaged parts of the brake-head and brake-supporting bracket will be taken up. It is important to here note that since the thrust-sleeve 15 is free to slide on the bolt 14 both the said parts are by one and the same adjustment of the nuts 18 drawn into frictional engagement with the seats and bearing-surfaces of the brake-head and its supporting-bracket.

The importance of being able to take up slack between the parts, so as to compensate for wear and to prevent clattering, is too obvious to need much comment. It is evident that such adjustments may be easily and quickly accomplished in my improved brake-hanger. It is also evident that the brake-head is supported so that it may freely move to carry the brake-shoe to and from contact with the wheel. It is further important to note that under the brake-setting action downwardly-tending forces applied to the brake-shoe from the wheel will be resisted by the tension-bolt 14, while upwardly-tending forces applied to the brake-shoe from the wheel will be resisted by the thrust-sleeve. In this way the work on the two parts of the brake-hanger will be divided between them; also, a solid or unyielding resistance under upwardly-tending forces on the brake-head is afforded.

The brake-hanger described is of simple construction, is very quickly applied in working position or removed therefrom, makes quick adjustments possible, and, furthermore, is exceedingly strong and durable.

It will of course be understood that the device described is capable of modification within the scope of my invention as herein set forth and claimed.

In the drawings the seat in the brake-head for the T-head of the tension-bolt 14 opens on the inner face of the brake-head, and the said bolt is held within its seat when the brake-shoe is applied to the brake-head; but it will of course be understood that the bolt-head seat might open at the rear face of the brake-head, so that the said bolt might be removed from working position without removing the brake-shoe. The construction illustrated, however, is believed to be better than the modification suggested.

From the relative functions of the parts, as hereinbefore described, it must of course be obvious that what I have called the "tension-bolt 14" may be regarded or termed the

"tension member" of the brake-hanger and that what I have called the "thrust-sleeve 15" might be termed the "compression member" of the brake-hanger. The said bolt or tension member 14 takes the strain applied to the brake-shoe from the wheels when turning downward in respect to the brake, and the said sleeve or compression member 14 takes the strain when the wheels are turning upward in respect to the brake, while at all times the brake is free for the requisite pivotal actions both at the brake-shoe and at the point of suspension from the frame-bracket. It is equally true that instead of the words "brake-hanger" used by me to include the tension-bolt and the thrust-sleeve or compression member that the said two devices might be collectively termed "a suspension device for brake-shoes," but it is thought that the term "brake-hanger" is the most appropriate and apt term for use for that purpose. Said tension-bolt 14 might also be called a "suspension-link."

What I claim, and desire to secure by Letters Patent of the United States, is as follows:

1. The combination with a brake-head, of a brake-hanger involving a pair of parts, one of which receives end thrusts and the other tension strains, in the brake-setting action.

2. The combination with a brake-head, of a brake-hanger made up of the telescoped parts pivotally supporting said brake-head, one part being arranged to receive end thrusts and the other tension strains, in the brake-setting action.

3. The combination with a brake-head and a supporting-bracket on the truck-frame, of a brake-hanger comprising a tension-bolt pivoted to said brake-head and to said supporting-bracket, and a thrust-sleeve on said bolt, between the brake-head and supporting-bracket, arranged to receive end thrusts, substantially as described.

4. The combination with a brake-head and a supporting-bracket said brake-head having an open seat formed with a slotted cylindrical bearing-web and said bracket having a slotted segmental bearing-web, of a tension-bolt working through the slotted web of said brake-head with its laterally-expanded head working within the seat thereof and with its upper end working through the slotted web of said bracket, a rocker seated in the concavity of the bearing-web of said bracket and through which the upper end of said tension-bolt is passed, nuts on the threaded upper end of said tension-bolt, and a thrust-sleeve on said tension-bolt bearing against the outer concave surfaces of the webs of said brake-head and bracket, substantially as described.

5. The combination with a brake-head and supporting-bracket, of a brake-hanger comprising a tension-bolt pivoted to said brake-head and to said supporting-bracket, a

thrust-sleeve on said bolt between said brake-head and said supporting-bracket, and means for adjusting one of the said parts to take up the slack, substantially as described.

5. In a car-brake, the combination with
brake-heads, hanger-brackets, and hanger-
rods for supporting said brake-head; said
hanger-rods having T-heads, the arms of

which are loosely seated in the hanger-brack-
ets and brake-heads, substantially as set forth. 10

In testimony whereof I affix my signature
in presence of two witnesses.
